UNITED STATES PATENT OFFICE.

PETER KELLER, OF NEW YORK, N. Y.

GAS-BURNER.

SPECIFICATION forming part of Letters Patent No. 280,482, dated July 3, 1883.

Application filed December 20, 1882. (No model.)

To all whom it may concern:

Be it known that I, PETER KELLER, a citizen of the United States, residing at New York, in the county and State of New York, have 5 invented new and useful Improvements in Gas-Burners, of which the following is a specification.

This invention relates to that class of burners in which a gravitating valve is used for 10 regulating the pressure of the gas; and it consists in the construction of the valve, together with its seat, of sheet metal, and in the arrangement of such parts, as hereinafter described, whereby the labor involved in the 15 manufacture of the burners is reduced to a minimum.

The invention is illustrated in the accompanying drawings, in which Figure 1 represents a vertical central section. Fig. 2 is a side view. 20 Fig. 3 shows the valve and valve-seat detached from the burner.

Similar letters indicate corresponding parts.

The letter A designates the shell of the burner, formed with a shoulder, o , on its lower part, 25 against which abuts the valve-seat B, supporting the valve C. Both said valve-seat B and valve C are made of sheet metal in form of inverted cups, they being struck up by means of suitable dies, and the valve-seat has a central upwardly-projecting nipple, s , through whose orifice the gas passes to act on the valve.

In carrying out my invention the valve-seat B is flared, as shown in Fig. 3, in such a manner that its largest diameter is greater than 30 the inner diameter of that portion of the burner situated below the shoulder o . The

seat is then forced into the burner from its lower end up to the shoulder o , and the seat being thus wedged against the side of the burner it is firmly held in position. Above the shoulder o in the shell A of the burner is formed a second shoulder, o' , of reduced diameter, and the space between said two shoulders forms a chamber for the working of the valve C, the upper shoulder limiting the movement of the 45 valve. Said upper shoulder, o' , also forms an abutment for a screen, e , which may be composed of wire-gauze or perforated sheet metal, and below the lower shoulder, o , the shell A is provided with an internal screw-thread for 50 its attachment to a gas-fixture.

It will be perceived that by making both the valve and valve-seat of sheet metal and arranging the same as above stated, the least labor is involved in the production of the 55 burner, and its cost is comparatively reduced.

What I claim as new, and desire to secure by Letters Patent, is—

The combination, substantially as hereinbefore described, of the burner-shell having the 60 shoulders o o' , the sheet-metal valve-seat wedged into the shell from its lower end to abut against the lower shoulder, and the sheet-metal valve resting on the seat, and working in the chamber formed by the upper shoulder. 65

In testimony whereof I have hereunto set my hand and seal in presence of two subscribing witnesses.

PETER KELLER. [L. S.]
